UNITED STATES PATENT OFFICE

2,528,691

HOUSING AND LOCKING MEANS THEREFOR

Herman O. Grimmeisen, West Springfield, Mass., assignor to Gilbert & Barker Manufacturing Company, West Springfield, Mass., a corporation of Massachusetts

Application June 6, 1947, Serial No. 752,964

2 Claims. (Cl. 312—215)

1

This invention relates to improvements in housings and locking means therefor.

The invention is suitable, for example, as an outdoor enclosure for such parts of a gasoline dispensing apparatus as need not be accessible to the service station attendant.

The object of the invention is to provide a housing with one or more removable panels or doors, normally locked in position by latching means, which are capable of being released with ease and convenience by improved means.

The invention will be disclosed with reference to the accompanying drawings, in which:

Figs. 1 and 2 are respectively front and side exterior elevational views of a housing for a gasoline dispensing apparatus embodying the invention;

Fig. 3 is a front elevational view of the housing, drawn to a larger scale and shown as it appears when the front panel of the casing is removed;

Fig. 4 is a top plan view with parts broken open to show the interior;

Fig. 5 is a sectional plan view taken on the line 5—5 of Fig. 3;

Fig. 6 is a fragmentary elevational view, taken in the same direction as Fig. 2 but drawn to a larger scale and having parts broken away and in section to show the means used to hold the front and rear panels of the casing in closed position;

Fig. 7 is a fragmentary view, taken similarly to Fig. 6 but showing one of the holding means in released position to enable removal of its panel;

Fig. 8 is a plan view of the holding means shown in Fig. 6; and

Fig. 9 is a fragmentary sectional plan view taken on the line 9—9 of Fig. 6.

Referring to these drawings and first to Figs. 1 and 2 thereof, the housing includes a base 1, a cap 2, left and right side panels 3 and 4, respectively, and front and back panels 5 and 6, respectively, these four panels enclosing the space between the base and cap. The particular housing shown is adapted to enclose parts of a gasoline dispensing apparatus. The front panel 5 has a window 6, through which the dial plate of the register is visible, an opening for the glass 7 of the visible discharge indicator and, if desired, an opening for a display sign 8. The back panel 6 is a duplicate of the front panel. On the side panel

2

3 is a crank 9 for resetting the register. The dispensing hose 10 issues through an opening 11 in the upper left hand part of side panel 4 and hangs in a loop, as shown in Fig. 2, with its nozzle 12, supported near the upper right hand part of the panel 4 and housed in a recess or boot 13. The hose loop may be retained by clips 14 on panel 4 which engage the sides of the loop near the bottom thereof. Also, on the panel 4 is a handle 15 for operating the switch of the driving motor to be described. On panel 4 is a flanged circular member 16, having openings 17 and 17' for use in unlocking the front and rear panels 5 and 6, respectively, after these openings have been uncovered by turning a key inserted in the centrally located lock 18, all as will hereinafter be described in detail.

Referring next to Fig. 5, four angle iron corner posts 20 are fixed at their lower ends to base 1. 20 These upstand from the base, as shown in Fig. 3, and support all other parts of the apparatus. The side panel 3 bridges across one pair of these posts 20 and the side panel 4 bridges across the other pair. Each side panel is similarly secured in place. Considering the side panel 4, for example, this has at its lower end (Fig. 5) an inturned flange 21, which is secured by cap screws 22 to base 1. Near its upper end, brackets 23 (Fig. 4) are welded to the panel 4, one near each side thereof, and the free end of each such bracket engages the adjacent corner post 20 and is suitably secured thereto, for example as shown in detail in Fig. 9 by a bolt 24. The upper ends of the corner posts 20 (Fig. 3) are connected by an inner cap 25, suitably secured to each post, for example as shown in Fig. 6 by a bolt 26. The described cap 2 rests upon the inner cap 25 and is secured thereto, as by bolts one of which is shown at 26' in Fig. 6. The sides of cap 2 along their lower edges have flanges 28 (Figs. 1 and 3) which overlap the upper ends of side panels 3 and 4. The front and back walls of the cap 2 are each cut away in the form of a flat arch, as shown in Fig. 3, and provided with a trough 29 (see also Fig. 6) to carry any moisture away to the sides of the apparatus where it can drip downwardly without doing any harm.

The front and back panels 5 and 6 are secured in place for convenient removal by authorized persons. Each of the panels 5 and 6 is secured

in the same way and a description of the means for fastening the panel 5 will suffice for both—corresponding parts for the panel 6 being designated by the same reference numerals primed. The panel 5 has at its lower edge an inturned flange 30 (Fig. 5) which rests upon the top of base 1. This flange is held against displacement in all directions except upwardly by means of two clips 31, which are secured one to each adjacent corner post 20 as shown in Fig. 3 and which pass through apertures in the flange 30. A rubber gasket 32 (Fig. 1) is suitably secured to the side and upper edges of panel 5 and is adapted to be pressed against the rounded sides of side panels 3 and 4 (Figs. 5 and 9) and against the front wall of cap 2 (Figs. 4 and 6) to provide a sealed joint. Fixed, as by welding, to the inner face of panel 5 centrally near the upper end thereof is a plate 33 (Figs. 6 and 7) which extends horizontally inward through openings 34 and 35 in caps 2 and 25, respectively, and has an opening 36 through its inner end to receive a latch 37. This latch is pivoted on a pin 38, fixed at its ends in the side walls of a U-shaped bracket 39 (Fig. 8), which in turn is fixed to a bracket 40, secured by bolts 41 to a depending side wall of cap 25. A spring 42 tends to move latch 37 into opening 36 and hold bracket 33 and panel 5 against outward movement. When the latch is released, by means to be described, the upper end of panel 5 can be swung outwardly enough to withdraw bracket 33 from holes 34 and 35 and then it may be lifted upwardly to carry the base flange 30 above clips 31, after which the panel may be removed.

The latch 37 is manually released by pushing inwardly on a push button 44 (Fig. 9), the push being transmitted by a Bowden wire 45 to the latch to lift the same from the position shown in Fig. 6 to that shown in Fig. 7. The button 44 is fixed to the outer end of a plunger 46, the inner end of which is slidably mounted in a tube 47. This tube is supported from a plate 48 which as shown in Fig. 4 spans the space between a pair of corner posts 20 and is secured at its ends one to each such post, as by bolts 48' (Fig. 9). The tube 47 passes through a hole in plate 48 and is clamped thereto between a flange 49 on the outer end of the tube and a nut 50 threaded on the tube. In the inner end of tube 47, one end of the sheath 51 for Bowden wire 45 is anchored. The wire itself is fixed at one end to the inner end of plunger 46 and at the other end to latch 37. The inner end of sheath 51 is anchored to a bracket 52 fixed to the described bracket 40. A spring 53 encompassing the plunger 46, acts between flange 49 and button 44 to draw the plunger 46 outwardly and thus draw wire 45 to hold the latch 37 in the position shown in Fig. 6. By pressing inwardly on button 44 the Bowden wire 45 is pushed to move latch 37 into the released position shown in Fig. 7.

The latch-releasing buttons 44 and 44' are accessible only through the holes 17 and 17' in the flanged circular member 16. This member overlies a large circular opening 54 (Fig. 6) in the panel 4 and it is secured to such panel, as by the bolts 55. The flange on member 16 (Fig. 9) spaces the face of the member away from the face of the panel 4 and in the space between these faces is mounted a plate 56, which is wide enough (Fig. 6) to cover both holes 17 and 17' and normally does so, thus preventing access to the buttons 44 and 44'. This plate 56 (Fig. 9) is centrally secured to the rear end face of the

cylinder 57 of a Yale lock 18, the barrel 58 of which is fixed centrally to the member 16 with the key hole accessible, when the pivoted rain shield 59 is swung out of the way, as into the dotted line position shown in Fig. 6. When the cylinder 57 is turned by means of the proper key, the plate 56 may be turned to uncover the holes 17 and 17', after which the operator can reach through either or both of the holes and press the button 44 or 44' or both as desired, to release the panel 5 or 6 or both.

It will thus be seen that the housing is locked up and access to the interior thereof can be had only by the one who is in control of the station and has the key for lock 18. The only way, in which access can be had to the interior of the housing, is by removing the front panel 5 or the back panel 6 and this can be done only after the cylinder 57 of lock 18 has been turned by the key to move the shutter 56 to uncover the openings 17 and 17'. Then, one can reach through the opening 17 or 17', press a button 44 or 44', whereupon the latch 37 or 37' will be moved to release the panel 5 or 6 respectively, and allow such panel to be removed. With the panels 5 and 6 removed access is had to all the interior of the housing. When access to the housing is no longer required, the panel or panels removed, are replaced. This is done by lifting the panel and, while held slightly tilted, placing its base flange 30 on the base 1 so that the clips 31 enter the holes in the base flange. The panel is then thrust inwardly into vertical position, whereupon the latch 37 will lock it in this position. As the panel 5, for example, is thrust inwardly, the plate 33 thereon cams the latch 37 upwardly and the latter compresses spring 42 and through Bowden wire 45 pulls push button 44 inwardly, compressing spring 53. As soon as the opening 36 in plate 33 comes into line with latch 37, the springs 42 and the spring 53, acting through Bowden wire 45, will pull the latch into opening 36 and lock the panel in place.

I claim:

1. In combination, a housing including a base, a cap and panels enclosing the space between the base and cap, one of said panels being removable and being located between two other panels which are fixed, a latch for holding the removable panel against removal, one of the fixed panels having an opening, operating connections including a push button located closely adjacent to and accessible through said opening for releasing said latch; a lock mounted on said one of fixed panels adjacent said opening and having a cylinder rotatable by a key when inserted in the lock; and a shutter movable by said cylinder from a position, in which it lies between said button and said opening and prevents access to the button, to a position, in which it uncovers the opening and enables one to reach through the opening to push said button and cause the release of said latch.

2. In combination, a housing including a base, a cap, and front, back and two side panels enclosing the space between the base and cap, said front and back panels each being removable and each being located between two side panels which are fixed; latches, one for holding the front panel against removal and one for holding the back panel against removal, one of the side panels having two spaced openings, push buttons, one for each latch and located inside the housing, one in back of each opening and accessible through such opening, a connection between each push button and its latch for moving the latch to

release its panel when the push button is pressed, a lock mounted on said one side panel between said openings and having a cylinder rotatable by a key when inserted in the lock, and a single shutter fixed centrally to said cylinder and having its ends severally covering said openings, said shutter being movable, when the cylinder is turned by the key in one direction, to uncover both openings and enable access to said push buttons and being movable, when the key is turned back to cover said openings, and prevent access to said push buttons.
